UNITED STATES PATENT OFFICE

JOSEPH H. KONIGSBERG, OF BROOKLYN, NEW YORK

DIPPER

Application filed July 6, 1928. Serial No. 290,797.

This invention relates to hand dippers, particularly those designed to dip out molten metal from one receptacle and to pour the metal into another, and contemplates the provision of means in such a dipper for screening and cleaning the metal during the transfer thereof. The various objects of my invention will be clear from the description which follows and from the drawings, in 10 which,

Fig. 1 is a top plan view of one form of my improved device wherein the screen is dispensed with.

Fig. 2 is a vertical, longitudinal section of 15 the same in the position in which metal is being poured from the dipper.

Fig. 3 is a similar view of another form of my invention in which an upper screen is provided.

Fig. 4 is a vertical section of the spout taken on the line 4—4 of Fig. 3.

Fig. 5 is a vertical, longitudinal section of a modified form of my improved dipper showing the screening deflecting plate, and, 25

Fig. 6 is a top plan view of the same.

In that practical embodiment of my invention which I have illustrated, the container portion or body 10 of the dipper is preferably of conical form, tapering inwardly toward the bottom 11 thereof, and is provided with a suitable preferably flat handle as 12, suitably secured to the rear of the body as by the rivets 13, one end 14 of the handle being bent downwardly for that purpose. 30 The inclination of the body 10 during the dipping and pouring operations is controlled by means of said handle.

The wire bail 15 is secured to the body 10 about midway between the front and rear 40 by means of suitable rivets 16 or the like passing through the flattened ends 17 thereof. The bail serves the usual purpose of providing means whereby the dipper may be lifted and supported.

At the front of the dipper is provided the spout 18 which is made preferably integral with the body 10, and in the modification shown in Figs. 1 and 2, may be provided with a downwardly turned lip 19 over which the metal may readily flow out of the dipper.

For separating out the dross or screen from the metal before it is poured out, I provide a deflecting plate as 20, which is in the form of a partition inserted into the dipper at the junction of the spout and the body. 55

Said plate substantially closes the opening at the rear of the spout, thereby normally preventing the material from flowing out through the spout excepting underneath said plate, and deflecting the floating dross away from the spout. As illustrated in Figs. 1 and 2, the bottom edge 21 of the plate 20 is spaced somewhat above the lower end of the spout, thereby providing the passage 22 through which material at the bottom of the body 10 may flow into the spout. 60

It will be seen that the dross or scum floating at the top of the molten metal in the dipper is prevented by the deflecting plate 20 from entering the spout and may, after the dipper has been nearly emptied, be readily removed. Since, however, some of the dross may flow out below the bottom edge 21 of the plate, when the dipper is almost empty, I prefer to provide an additional top screening element as 23, closing the upper end of the spout and preventing material from leaving the dipper except through the comparatively small openings 24 in said element. For maintaining the element 23 in place, the edges 25 of the spout may be bent over to provide a channel or groove as 26 in which said element may be removably or securely held, as may be found convenient or desirable. One end of the element rests on the shoulder 27 of the lip 28, while the other end may be supported by the upper edge of the deflecting plate 20, or 31. 75

In the modification shown in Figs. 5 and 6, the deflecting plate 31 is lengthened to engage the sides and bottom of the spout as at 30 and to close the passage 22. For allowing material to pass said plate, it is provided with a series of openings 29 near the lowermost part thereof, which openings serve to screen out the dross and prevent the foreign matter from entering the spout at all. 85

It will be understood that the deflecting plate 20 or 31 may be used with or without the top screening element 23, as may be desired. 100

While the plate 20 may be welded or brazed to the inside wall of the body 10, as shown in Figs. 1, 2 and 3, if it is desired to support such a plate removably, as illustrated in Figs. 5 and 6, suitable means therefor may readily be provided. Such means may include the members 32 bent to provide suitable grooves as 33 for the reception of the plate 31, and flanged as at 34. Suitable means are used to 10 secure the flanges 34 to the dipper body, though the flanges may readily be welded in place, if desired.

Molten metal or other material may be dipped out of a container by supporting the 15 dipper, the bail 15 being held in one hand and the handle 12 in the other. The spout of the dipper is then lowered by raising the handle and the front part inserted into the container. Material flows into the dipper through the 20 open top of the body and the spout until sufficiently filled. The filled dipper is then lifted out by the bail and carried to the container for receiving the material, and the handle 12 again inclined, lowering the spout and allowing 25 the material to flow past the lower edge of the plate 20 or 31, as the case may be. Dross is prevented from leaving the body 10 and entering the spout by said plate.

Where perforated screening plates are used, 10 only the heavier material, such as clean molten metal can flow through the perforations of the plates, the dross being left behind and readily removed from the dipper.

In its entrance into the dipper through 15 the screening element 23, should the metal carry any dross, the dross is kept out by said plate and remains on the top thereof, whence it may be easily wiped off.

It will be seen that I have provided simple 20 and effective means for preventing foreign matter from leaving the dipper and for screening all such foreign matter from the material flowing from the dipper.

While I have shown and described a preferred embodiment of my invention, I do not 25 intend to be understood as limiting myself to the specific structure shown and described by way of example, but intend to claim my invention as broadly as may be permitted by the 50 state of the prior art and the terms of the appended claims.

I claim:

1. A dipper comprising a container member, a spout integral therewith and communicating with the container member, a plate interposed between the spout and the container member for cutting off communication therebetween except through the bottom of said plate, a pair of L-shaped members coextensive with the height of the spout and arranged at the juncture of the sides of the spout with the sides of the container member and forming a pair of grooves therebetween for the reception of said plate, a perforated 60 plate closing the top of said spout and means 65

on said spout for holding the perforated plate in operative position, comprising a depressed lip at the outer end of the spout and horizontally disposed grooved edges on the top of the spout, the inner end of said perforated plate being adapted to rest on the top of said first- 70 mentioned plate.

2. In a dipper, a spout, a shoulder at the forward edge of said spout, inturned portions providing grooves at the side of said spout and a perforated plate closing the top of said spout, resting on said shoulder and inserted into said grooves.

3. The combination with a dipper having a spout provided with a rectangular top opening and a rectangular rear opening where the spout joins the remainder of the dipper, of a removable perforated plate for closing the top opening, grooved, horizontal side edges on the top of the spout adapted to removably receive said plate, a pair of substantially vertical retaining members L-shaped in cross-section arranged at the rear of the spout and of substantially the height of the spout and providing grooves between said member and the dipper, and a perforated plate of substantially the height of the rear opening of the spout inserted in the grooves provided by said L-shaped members and substantially closing said rear opening except at the bottom thereof.

JOSEPH H. KONIGSBERG.
